(12014 Old St. Charles Road, Bridgeton, Mo.)

Filed Nov. 17, 1959, Ser. No. 58,374

Term of patent 14 years

(Cl. D14—27)

FIG. 1.

FIG. 4

FIG. 3.

FIG. 1 is a side elevation of a collapsible camping compartment showing my new design in a closed position;

FIG. 2 is a side elevation thereof, in open position;
FIG. 3 is a top plan view thereof;

FIG. 4 is a sectional view taken on line 4—4 of FIG. 3.
The portions of an automobile shown in the broken lines are included for illustrative purposes only.

The side not shown is a mirror image of the side shown and the ends are substantially plain.

I claim:

The ornamental design for a collapsible camping compartment, as shown and described.
